CONTINUOUS COLUMN CLIP

Dewey H. Bitney, Albion, Mich., assignor to
Union Steel Products Company, Albion, Mich.

Application April 16, 1936, Serial No. 74,720

10 Claims.

(Cl. 72—76)

This invention relates to improvements in continuous column clips.

The main objects of my invention are:

First, to provide a continuous wire column clip 5 adapted for use in connection with reinforced concrete beams and columns.

Second, to provide a clip of the type described, which is characterized by its efficiency and economy.

10 Third, to provide a clip of the type described, which may be readily and quickly applied to a structural steel column, beam or girder preparatory to the pouring of concrete.

Fourth, to provide a clip of the type described, 15 which furnishes reinforcing for concrete at all points relative to the member, adjacent both the web and the flange thereof.

Fifth, to provide a clip of the type described, 20 which may be locked about a beam or column without regard to the particular shape of the same.

Further objects relating to details and economies of my invention will definitely appear from the description to follow. The invention is defined in the claims.

A preferred embodiment of my invention is illustrated in the accompanying drawing, wherein:

Fig. 1 is a perspective fragmentary view of an I beam or column embraced by the clip of my invention and in readiness for the pouring of concrete therearound.

Fig. 2 is a vertical sectional view of the clip illustrated in Fig. 1, showing details of my inventive structure.

35 Fig. 3 is a perspective view similar to Fig. 1, the column being omitted to more clearly illustrate the operative relation of the elements of my construction.

In the pouring of concrete about steel beams, 40 columns, girders and the like, it is necessary to provide reinforcing members for the concrete, and such members are relatively desirable to the extent that they are cheap, simple in construction, readily assembled, universal in application to a 45 variety of shapes of column section, and efficient in their manner of providing reinforcing for the concrete. I have devised a column clip which is characterized by each of the above essentials to a remarkable degree.

50 In the drawing, reference numeral 1 indicates an I beam adapted for use as a column or beam; however, it is to be understood that my invention is not limited to an application in connection with an I beam, but may be employed with 55 a variety of different structural forms and sec-

tions not illustrated. My column clip comprises a plurality of pairs of complementary unitary U-shaped transverse wire members having arms 2, 3 of unequal length. The transverse members are bent to provide coils 4 at the bases of the 5 arms and adjacent the cross member 5 of the U-shaped transverse members. The purpose of the coils is to space the cross member 5 from the flange 6 of the beam 1 so as to adequately reinforce the concrete column at that point. 10

The corresponding U-shaped transverse members are secured in fixed spaced relation by longitudinal wires or members 7 extending longitudinally of the column or beam and at right angles to the transverse members, being welded 15 to the cross portions of the transverse members at 8. Further longitudinally extending members 9 are welded to the longer arms 2 of the transverse members, preferably at the ends thereof. I have shown members 9 as being connected to the longer arms 2; however, it will be understood that the longitudinal members 9 might with equal effectiveness be suitably secured to the shorter arms 3. The former construction, however, is preferable inasmuch as it is found that on the 20 whole a longitudinal support for the shorter arms is not necessary; hence the use of an additional wire is eliminated. The longitudinal members 9 furnish at once a spacing means for maintaining the transverse members at predetermined 25 distance from one another and for furnishing an anchor by means of which the U-shaped members may be locked about a column. As clearly illustrated in the drawing, the locking is effected by looping arms 3 of each unit about the longitudinal members 9 and back upon themselves. 30

Advantages of the clip so described lie in the fact that it is cheap and simple and speeds installation on the job. It also provides adequate reinforcement across the web and flange of the 40 column, inasmuch as it completely encloses the structural section, resulting in a very practical column reinforcement.

My reinforcement unit is locked entirely independently of the structural shape which it encloses. That is to say, it depends in no manner upon the shape of the column to afford it a locking anchorage. Universality of my clip is therefore obvious. Further, a structure is provided which effects maximum economy of material, 45 hence results in inexpensive manufacture.

I have illustrated and described my improvements in an embodiment which I have found very practical. I have not attempted to illustrate or describe other embodiments or adaptations which 55

I contemplate, as it is believed this disclosure will enable those skilled in the art to embody or adapt my improvements as may be desired.

Having thus described my invention, what I claim as new and desire to secure by Letters Patent is:

1. In a continuous column clip, the combination of a plurality of opposed pairs of U-shaped transverse members of wire, each having a pair of arms of unequal length, a cross piece and coils between the arms and cross piece, the coils acting to space the clip from the flange of a column which the members embrace transversely, and longitudinal members of wire welded to the longer arms of the transverse members at the ends thereof and to the cross pieces of the transverse members whereby the transverse members are secured in fixed spaced relation, the shorter arms of said transverse members being looped around the longitudinal wires fixed to the longer arms of the transverse members to lock the clip upon a column.

2. In a continuous column clip, the combination of a plurality of opposed pairs of U-shaped transverse members of wire, each having a pair of arms of unequal length, a cross piece and coils between the arms and cross piece, the coils acting to space the clip from the flange of a column which the members embrace transversely, and longitudinal members of wire secured to the longer arms of the transverse members and to the cross pieces of the transverse members whereby the transverse members are secured in fixed spaced relation, the shorter arms of said transverse members being looped around the longitudinal wires fixed to the longer arms of the transverse members to lock the clip upon a column.

3. In a continuous column clip, the combination of a plurality of opposed pairs of U-shaped transverse members of wire having coils at the bases of the arms, the coils acting to space the clip from the flange of a column which the members embrace transversely, and longitudinal members of wire secured to one arm of each transverse member and to the cross pieces thereof whereby the transverse members are secured in fixed spaced relation, the free arms of said transverse members being looped around the longitudinal wires fixed to the arms of the associated unit to lock the clip upon a column.

4. A column clip unit comprising a plurality of U-shaped transverse members of wire having arms of unequal length and spacing coils at the bases of the arms, a longitudinal member of wire welded to the longer arm of the transverse members adjacent the ends thereof, and a second longitudinal wire welded to the cross portion of said transverse members whereby the transverse members are secured together in a fixed spaced relation and the unit is adapted for locking association with a corresponding unit in embracing relation to a column by looping the ends of the shorter arm of one unit around the longitudinal

member secured to the longer arm of the associated unit.

5. A column clip unit comprising a plurality of U-shaped transverse members having arms of unequal length and spacing offsets at the bases of the arms, a longitudinal member secured to one arm of each transverse member, and a second longitudinal wire secured to the cross portions of said transverse members whereby the transverse members are secured together in a fixed spaced relation and the unit is adapted for locking association in a corresponding unit in embracing relation to a column by looping the ends of the free arms around the longitudinal members secured to the arms of the associated unit.

6. A column clip unit comprising a plurality of U-shaped transverse members having extending arms and spacing offsets at the bases of the arms thereof, and a longitudinal member secured to one arm of each transverse member, said member being secured to said arm at a point on the arm adjacent the outermost end thereof.

7. In a column clip, a plurality of U-shaped unitary wire members having arms of unequal length and spacing coils at the base of said arms, said members being adapted for locking association with corresponding wire members in embracing relation to a column, and longitudinal wires welded to said U-shaped members and spacing them lengthwise of the column, at least one of said wires being welded to the corresponding arms of said members at points closely adjacent the outermost ends of said arms.

8. In a column clip, a plurality of U-shaped unitary wire members having arms and spacing coils at the base of said arms, said members being adapted for locking association with corresponding wire members in embracing relation to a column, and a longitudinal wire secured to said U-shaped members, said wire being secured to the corresponding arms of said members at points closely adjacent the outermost ends of said arms.

9. In a column clip, a plurality of unitary wire members terminating in parallel arms and having spacing coils at the base of said arms, said members being adapted for locking association with corresponding wire members in embracing relation to a column, and a longitudinal wire secured to said members, said wire being secured to the ends of corresponding arms of said members.

10. In a column clip, a plurality of U-shaped unitary wire members terminating in parallel arms of unequal length, said members being adapted for locking association with corresponding opposed wire members in embracing relation to a column, and longitudinal wires secured to the outermost ends of the arms of said U-shaped members and spacing them lengthwise of the column, an arm of each of said members being wrapped around a longitudinal wire on an opposed member to effect said locking association.

DEWEY H. BITNEY.
